WILHELM GENSECKE, OF HOMBURG, NEAR FRANKFORT-ON-THE-MAIN, GERMANY,
ASSIGNOR TO AMERICAN LURGI CORPORATION, OF NEW YORK, N. Y., A CORPORA-
TION OF NEW YORK

METHOD AND APPARATUS FOR HEATING STILLS

Application filed May 18, 1928, Serial No. 278,818, and in Germany May 27, 1927.

This invention relates to a method and apparatus for heating indirectly with steam stills in which high boiling substances, such as fatty acids, whose boiling point rises considerably in the course of the distillation, are distilled.

The heating of stills, in which high-boiling substances such as fatty acids, are to be distilled, generally is done by direct flames.

10 It has also been proposed, to heat the stills by hot water produced in a special boiler, which is heated separately. Finally it is obvious, to heat the stills with steam. This steam has however to be produced in a special 15 high pressure boiler, in order to obtain a sufficiently hot steam. The pressure of the boilers normally used in the art is about 12 atmospheres and the corresponding temperature of the steam is at about 190° C., 20 whereas stills often must be heated to far higher temperatures, such as for example up to about 250° C., when fatty acids are to be distilled.

25 The direct heating of stills has disadvantages. It is then not easy to regulate the temperature in the still, and local superheatings of the material to be distilled may often take place. Also the other heating methods have disadvantages, which are mainly due 30 to the fact, that a separate boiler with separate furnace has to be present.

These disadvantages are avoided according to the invention, which relates to an important simplification for heating stills. 35 The invention is characterized by the fact, that the heating of the content of the still and the distillation of the lower boiling fractions is carried out by normal steam, coming from a boiler and that the higher temperature of the steam necessary for the distillation of the higher boiling fractions is automatically produced by a steam-compressor pump, arranged between the steam boiler and the heating system of the still. The first 40 heating of the content of the still, until distillation begins, may be carried out quickly, as the steam coming from the steam conduit is present in great amounts. Also the distilling off of the lower boiling fractions may be 45 carried out with ordinary boiler steam, in

case the distillation takes place at a high vacuum. If during the distillation the temperatures necessary exceed the temperature of the boiler steam, the steam-compressor between the boiler and the still is switched in, thus 55 automatically producing a pressure corresponding to that temperature of the necessary steam for heating the still. It is thus attained, that the energy necessary for the compression of the steam and for the heating 60 of the still, is economized as much as possible. The intensity of the heating may be regulated for example by changing the number of rotations of the steam-compressor pump. The expenses for a pump and for 65 driving a pump compared with the expenses for providing and driving a special heat producer are far lower.

In the annexed drawing the invention is 70 illustrated by way of example. *a* is the steam boiler, *b* the still, *c* the heating coil in the still. The heating of the still is started by introducing normal boiler steam through the conduit *d* into the heating-coil *c*. The valve *e* is opened during the heating with 75 normal boiler steam. *f* is a steam-compressor pump, which during the start of the operation is disconnected by valves *g* and *h*. When the highest temperature, which may be obtained by the use of direct steam, is 80 reached in the still, the valves *g* and *h* are opened and the steam pump *f* is preheated and prepared for operation. *i* is a valve for removing condensed water from the pump, which is if necessary opened during the pre-heating of the pump. When the pump *f* is 85 ready for working, it is started, there being no pressure differences to be overcome by the pump at first. Then the valve *e* is closed and the steam is introduced into the coil *c* by 90 the pump *f*. By the addition of heat dependent upon the out-put of the pump, the temperature in the still is raised slowly, whereby the higher boiling fractions are 95 distilled off. *k* is a safety valve, preventing the exceeding of a certain maximum pressure and maximum temperature in the coil *c*. The condensate in the heating coil *c* is caught by the separator *l* and conducted away by suitable means such as steam-pots or the like. 100

There may also be arranged two steam pots one behind another, the first pot being in connection with the suction tube of the steam-pump. One may thus introduce the amount 5 of steam primary relieved into the heating coil by the pump.

I claim:

1. Process of distilling a high boiling mixture comprising components having different boiling temperatures by indirectly heating 10 said mixture with steam which comprises taking steam from a supply thereof at a substantially constant temperature and pressure, said temperature being below the distillation temperature of said mixture, compressing the steam whereby it is brought to a temperature suitable for the distillation and bringing the compressed steam into indirect heat transfer relation to said mixture.
- 20 2. Process of distilling materials having different boiling temperatures by indirect heating with steam which comprises taking steam from a source of supply at substantially constant temperature and pressure, said 25 temperature being below the distillation temperature of said materials, compressing the steam whereby its temperature is raised to a temperature sufficient for the distillation of said materials and bringing the compressed 30 steam into indirect heat transfer relation to said materials.
3. An apparatus comprising a steam 35 boiler, a still, heating means in said still for heating the same indirectly with steam, a steam conduit connecting said boiler with said heating means, a steam compressor whose suction side is connected to the steam boiler and whose pressure side is connected to said heating means, means to connect and 40 disconnect said steam conduit with said heating means and means to connect and disconnect said steam compressor with said heating means.

In testimony whereof I affix my signature,
45 WILHELM GENSECKE.
